UNITED STATES PATENT OFFICE.

ALLAN ROLAND PYE JOHNSON, OF TORONTO, ONTARIO, CANADA.

LOCKING DEVICE FOR BULB SUPPORTS OF DIRECTION INDICATORS.

Application filed March 19, 1928. Serial No. 262,787.

My invention relates to improvements in locking devices for bulb supports of direction indicators, and the object of the invention is to devise simple means for releasably locking the illuminating bulb supports in place so that they may be readily removed whenever desired, and it consists essentially of the arrangement and construction of parts as hereinafter more particularly explained.

Fig. 1 is a sectional view through a portion of the back wall and a wall vertical thereto and the incandescent bulb and bulb support, the bulb being shown in elevation and the support partially in section and partially in elevation.

Fig. 2 is a sectional plan view on line 2—2 Figure 1.

In the drawing like characters of reference indicate corresponding parts in each figure.

1 indicates a portion of a back wall of a direction indicator casing. 2 is a wall extending at right angles thereto and forming part of a direction indicating chamber. 3 is an orifice formed in the wall 2. 4 is a boss extending from the back wall and from the wall 2 and provided adjacent the wall 2 with a recess 5.

10 The recess 5 may be made concentric to the centre of the orifice 3, but this is not essential.

The incandescent bulb support is in the

form of a sleeve 6 in which the bulb base 7 is secured by means of a pin or pins 7^x extending into corresponding bayonet slots 6^x.

8 is a spring contact pin of any suitable construction mounted within the sleeve 6. 9 is an annular flange extending around the sleeve 6, a portion of which is cut off as indicated at 9^x.

When it is desired to place my bulb support in position all it is necessary to do is to pass the sleeve 6 through the orifice 3 so that the cut off portion 9^x is opposite the boss 4. When the flange 9 is brought opposite the recess 5 the support is turned into the position shown in Figure 2 so that the flange enters the recess 5 thereby securely locking the bulb support in place from withdrawal.

What I claim as my invention is:—

The combination with two wall portions set at right angles one to the other, one of said portions having an orifice therein, a recess formed in the other wall portion adjacent the orifice, a sleeve forming a support for an incandescent bulb and coacting contacts and fitting the aforesaid orifice and provided with an annular flange having a cut off portion adapted when the sleeve is turned to permit the flange thereof clearing the recess to permit of the withdrawal of the sleeve.

ALLAN ROLAND PYE JOHNSON.
